US00D516767S

(12) **United States Design Patent** (10) Patent No.: **US D516,767 S**
(45) Date of Patent: **** Mar. 7, 2006**

(54) **ROTATABLE ARTICLE ENGAGING ASSEMBLY**

(75) Inventor: **James L. Layne**, Bowling Green, KY (US)

(73) Assignee: **Span Tech LLC**, Glasgow, KY (US)

(**) Term: **14 Years**

(21) Appl. No.: **29/210,032**

(22) Filed: **Jul. 26, 2004**

Related U.S. Application Data

(63) Continuation of application No. 10/672,250, filed on Sep. 26, 2003, now Pat. No. 6,874,617.

(51) **LOC (8) Cl. 12-05**

(52) **U.S. Cl. D34/29**

(57) **CLAIM**

The ornamental design of a rotatable article engaging assembly, as shown and described.

DESCRIPTION

FIG. 1 is a perspective view of the rotatable article engaging assembly of the present invention;

FIG. 2 is a perspective view thereof;

FIG. 3 is a top plan view thereof;

FIG. 4 is a front elevational view, the rear being a mirror image thereof; and,

FIG. 5 is a right side elevational view, the left side being a mirror image thereof.

The broken lines in FIGS. 1 through 5 are for illustrative purposes only and form no part of the claimed design.
